UNITED STATES PATENT OFFICE.

ROMAN B. BUKOLT, OF STEVENS POINT, WISCONSIN.

SIDE-LOCKING MEANS FOR BASSINETTS.

Application filed February 17, 1927. Serial No. 169,064.

This application is a continuation in part of my pending U. S. application Serial No. 124,413, filed on or about July 23, 1926.

Like the original application, the present case is devoted to locking means designed primarily for use in connection with drop sides of bassinets, and the aim of the invention is to provide a new and improved means for holding a drop side in elevated position, said means being of exceptionally simple and inexpensive, yet efficient and desirable construction.

With the foregoing in view, the invention resides in the novel subject matter herein-after described and claimed, the description being supplemented by the accompanying drawings.

Fig. 1 is a side elevation partly in section showing a bassinet provided with the improved locking means.

Fig. 2 is a fragmentary side elevation of the drop side and associated parts, looking in the opposite direction from Fig. 1.

Fig. 3 is an enlarged elevation of the central portion of the locking means.

Fig. 4 is a horizontal sectional view on line 4-4 of Fig. 3, looking in the direction of the arrows.

Figs. 5 and 6 are vertical transverse sections on the correspondingly numbered lines of Fig. 4.

Fig. 7 is a perspective view of the spring-retaining housing shown more particularly in Figs. 3 to 6.

Fig. 8 is a detail transverse section on line 8-8 of Fig. 2.

Fig. 9 is a fragmentary elevation partly in section, of the parts at one upper corner of the drop side.

Fig. 10 is a horizontal sectional view on line 10-10 of Fig. 9 looking in the direction of the arrows.

In the drawings above briefly described, the numbers 11 designate two corner posts of a bassinet, and 12 denotes a drop side therefore, said drop side having upper and lower horizontal rails 13 and 14, the ends of these rails being formed with vertical openings 15 which slidably receive vertical rods 16 carried by upper and lower brackets 17 and 18, and intermediate brackets 19, all secured to the posts 11. Rubber bumpers 20 preferably surround the rods 16 and rest upon the brackets 18, to engage the lower rail 14 of the drop side 12, when the latter is lowered.

Disposed longitudinally under one of the

rails 13-14 (in the present instance under the rail 13) are two rods 20, the major portions of said rods being received in a groove 21 formed longitudinally in one lower corner of this rail. The outer ends 22 of these rods 20, are offset both vertically and horizontally from the major portions of said rods, and are positioned at the central longitudinal portion of the rail 13, screw eyes or the like 23, being provided to slidably receive said rod ends 22. These ends are engageable with circumferential grooves 24 formed in the upper portions of the rods 16, for the purpose of holding the drop side 12 in its elevated, operative position.

The inner ends of the rods 20 are bent horizontally outward as at 25 and are preferably provided with knobs 26, disposed at the outer side of the rail 13. Interposed between these lateral rod ends 25 and extending longitudinally of the rail 13, is a coiled compression spring 27 which engages both of said lateral rod ends to project the rods and normally hold them in engagement with the grooves 24.

A horizontally elongated, channel-shaped member 28 is provided to contain the spring 27, and the end portions of the side walls of this member contact with the lower sides of the rod ends 25, assisting in slidably mounting the rods. The end portions of one side wall of the member 28 preferably have straight upper edges 29 contacting with the rod ends 25, while the corresponding portions of the other side wall, may well be provided with outwardly turned horizontal flanges 30 engaging said rod ends. Between the end portions 29-30, the walls of the member 28 are preferably of greater height than at said end portions, as denoted at 31 and 32 respectively, these portions 31 and 32 being intended to abut the lower side of the rail 13 to space the portions 29-30 downwardly therefrom, sufficiently to permit free sliding of the rod ends 25.

For the purpose of attaching the member 28 to the rail 13, I prefer to provide the portion 32 with an outwardly extending lug 33 at its upper edge, said lug having an opening to receive an attaching screw or the like 34. When a screw is used, a lock washer 35 is preferably employed for the same.

By preference, the member 28 is provided with end walls 36 which project beyond the open or upper side of said member. These end walls may well serve as stops for limiting

the outward movement of the rods 20, by engagement with the lateral rod ends 25.

The member 28 with the details of construction above described, may well be stamped from a single piece of sheet metal and such construction has been herein disclosed.

In addition to the features of construction above described, for slidably mounting the rods 20 in the groove 21, I prefer to secure 10 sheet metal plates 37 to the lower side of the rail 13, said plates having curved ends 38 of substantially 90° in length. The two side walls of the groove 21 and the curved ends 38 of the plate 37, jointly surround the rods 20 15 and assist materially in slidably mounting said rods in the desired manner.

By grasping the knobs 26 and moving them toward each other, the rods 20 are inwardly slid against the action of the spring 27, thereby 20 disengaging the rod ends 22 from the grooves 24 and permitting lowering of the drop side 12. When this side is again raised, the spring 27 slides the rods 20 outwardly into 25 engagement with the grooves 24, as soon as the drop side reaches its raised position, so that it is automatically latched in such position.

The entire construction is exceptionally 30 simple and inexpensive, yet will be efficient and in every way desirable. On account of the excellent results which have been obtained from the details disclosed, they are preferably followed. However, within the scope of the invention as claimed, variations may be made.

35 I claim:—

1. A locking means for a member having a rail; said locking means comprising a pair of locking rods extending longitudinally of and 40 slidably connected with said rail, the inner ends of said rods being turned laterally in spaced relation to form means for inwardly sliding the rods to released position, a horizontally elongated channel-shaped guide member of very short length compared with 45 the lengths of said rods, said guide member extending longitudinally of the intermediate portion only of said rail, having an exposed longitudinal edge spaced from and parallel with said rail, and being secured to the latter, 50 said lateral rod ends being disposed between

said rail and said longitudinal edge of said channel-shaped guide member, and a coiled spring disposed longitudinally of said guide member with its ends in contact with said lateral rod ends, said spring serving to project 55 the rods.

2. A structure as specified in claim 1; said channel-shaped guide member having end walls disposed in the outward paths of said lateral rod ends to limit the projection of the 60 rods.

3. In a locking means of the class described, an elongated channel-shaped spring-retaining member having end walls which project beyond its open side, one longitudinal side 65 wall of said member being increased in width at its central portion and being provided with an attaching lug projecting laterally outward from the outer edge of said widened portion.

4. In a locking means of the class described, 70 an elongated channel-shaped spring-retaining member having end walls which project beyond its open side, the central portion of the side walls of said member being of greater height than the end portions of said walls, 75 one of said central portions having an integral laterally projecting attaching lug at its free edge.

5. A locking means for a member having a rail; said locking means comprising a pair of 80 locking rods extending longitudinally of and slidably connected with said rail, the inner ends of said rods being turned laterally in spaced relation to form means for inwardly sliding the rods to released position, a horizontally elongated guide member with which 85 said lateral rod ends contact slidably, said guide member being secured to said rail, and a spring engaging said guide member and exerting an outward force on both of said lateral rod ends to project the rods, said rail being longitudinally grooved in one lower corner to receive the body portions of said rods, the outer ends of said rods being offset both 90 vertically and horizontally from said body portions and disposed at the central longitudinal portion of one side of said rail. 95

In testimony whereof I have hereunto affixed by signature.

ROMAN B. BUKOLT.
